BAKE OVEN CONVEYER

John R. Nalbach, Oak Park, and Adolph Haupt,
Chicago, Ill., assignors to Middleby-Marshall
Oven Co., Chicago, Ill., a corporation of Illinois

Application March 23, 1942, Serial No. 435,774

6 Claims. (Cl. 198—137)

This invention relates to improvements in bake oven conveyer.

One object of the invention is to provide an improved oven of the traveling type provided with tray supporting and moving means of such character that the height of the baking chamber may be substantially less than the height of conventional pendant tray traveling ovens, thereby reducing the quantity of material, including insulation, required in the construction of the oven side walls and providing a relatively smaller area to be heated.

Another object of the invention is to provide a traveling tray oven provided with pan supporting trays which are stabilized or positively supported in horizontal position throughout the path of travel thereof within the baking chamber.

An additional object of the invention is to provide an improved oven of the type mentioned wherein the pan trays are positively supported horizontally throughout the path of travel thereof and mechanism enabling the tray moving mechanism to be operated in either direction.

Other objects relate to various features of construction and arrangement of parts which will be apparent from a consideration of the following specification and accompanying drawings, wherein.

Figure 1 is a vertical sectional view of an oven embodying the present improvements, the section being taken on line 1—1 of Fig. 2;

Fig. 2 is a horizontal sectional view taken on line 2—2 of Fig. 1;

Fig. 3 is an enlarged broken detached sectional view illustrating the tray carrying and stabilizing mechanism of the oven, the section being taken on line 3—3 of Fig. 4;

Fig. 4 is a broken plan view of the mechanism shown in Fig. 3;

Fig. 5 is a broken vertical sectional view taken on line 5—5 of Fig. 3;

Fig. 6 is a broken top plan view of a portion of a lower track and track switch;

Fig. 7 is a perspective view illustrating an adjustable mounting for certain of the operating parts of the mechanism.

In the drawings, 10 generally indicates an oven enclosure which may be constructed in any approved manner and of any suitable materials and comprises a front end wall 11, provided with a loading and unloading opening 12 (no closure therefor being shown), a rear wall 13, side walls 14, 15, a top or roof 16 and a base or floor 17.

The particular heating means used in supplying heat to the oven is not particularly pertinent to the present invention, but for the purpose of illustration a fire box 18 is shown at the rear 5 end of the oven from which hot gases pass into a longitudinally extending centrally located duct 19 which, adjacent the forward end of the oven, communicates with a transverse header 20. The hot gases flow from the header through heat radiating tubes 21 which at their rear ends communicate with a transverse gas receiving duct 22 from which extends an exhaust duct 23.

Above the heat radiating tubes is the baking chamber within which traveling mechanism of the oven is located. This mechanism, in the form illustrated, comprises a pair of endless chains, indicated generally by numerals 24 and 25, which are trained over a pair of sprockets 26 and 27 adjacent the forward end of the baking chamber and over a second pair of sprockets 28 and 29 adjacent the rear end of the oven.

The sprockets 26 and 27 are mounted on a driven shaft 30 extending transversely of the oven, and in the form of the invention illustrated 15 projects beyond the side walls thereof. A sprocket 31 is mounted on one end of the shaft 30 over which passes a drive chain 32 by means of which the shaft can be driven from any source of power such as a motor 33 shown in Fig. 1. The motor 20 may be of the reversible type or a suitable reversing clutch mechanism may be employed for driving the shaft 30 in either direction for operating the conveyer chains 24 and 25 in the desired direction. The sprockets 28 and 29 are 25 mounted on stub shafts 28^a, 29^a respectively, as will be later described.

The upper and lower horizontal runs of each chain are supported by upper and lower tracks 34 and 35, respectively, which are secured to the 30 lower side walls or frame of the oven and hence support the loads imposed thereon without sagging. The pintles or pivots of the chain links are provided with rollers 36 which contact the tracks for reducing friction.

45 For supporting the pans of bakery products to be baked, trays 37 are provided, the trays being attached to the chains and being movable therewith. In Fig. 2 of the drawings the trays are shown as comprising metal frames 37^a which 50 have upwardly directed flanges 37^b at the ends and rear thereof and foraminous or reticulated members 37^c upon which the bake pans rest and through unobstructed portions of which vertical circulation currents can pass.

55 The trays 37 do not hang pendant from the

traveling chains but are supported positively at their front and rear corners throughout their movements and hence are stable in all positions. Due to the fact that they are so supported they and their supporting means require less vertical space for accommodating their movements and hence the baking chamber of the improved oven may be less in height than conventional traveling ovens and the loading door 12 may also be nearer the floor, that is, it may be substantially at table height if desired, and hence the loading and unloading operations when performed by hand are much less difficult as compared with ovens the loading doors of which are at a substantially greater distance from the floor.

The trays 37 are pivotally attached adjacent the rear ends thereof to the chains 24 and 25 by means of pintles or rods 37^d which constitute the pins or pivots of certain of the chain links as illustrated in Fig. 3. The forward ends of the trays are provided with laterally projecting pins 37^e, having rollers thereon which generally roll on the tracks 34 and 35 whereby the trays are supported positively against tilting during the horizontal portions of the movements of the respective trays.

Mechanism is provided for stabilizing the trays during the movements from the upper to the lower as well as from the lower to the upper horizontal runs of the conveyer. This mechanism in the form illustrated comprises a pair of rotatable transfer arms 38 located forwardly of the sprockets 26, 27 and a second pair 47 of such arms located forwardly of the rear pair of sprockets 28 and 29. The arms 38 are mounted on stub shafts 38^a journaled suitably in the oven wall or frame work and are provided with sprockets 40 at their outer ends over each of which passes a chain 41 to sprockets 42 mounted on the shaft 30 as shown in Fig. 2. As the shaft 30 operates, the stub shafts 38^a will be rotated in timed relation therewith due to the fact that the sprockets 40 and 42 are of like diameter. The transfer arms 38 correspond in length to the diameter of the sprockets 26 and 27 and at their ends are provided with sockets or recesses 38^b for receiving therein the forward roller supporting pins 37^e of the respective trays.

Referring to Fig. 3, let it be assumed that the upper run of the chain 25 is moving from right to left. Tray indicated by letter A is approaching the end of its horizontal travel but in that position is supported at its forward end by the roller pin 37^e which still contacts the track 34, the end 34^a of which is wider horizontally than the intermediate portion thereof. As the pin 37^e of tray A reaches the end of the track 34, the tray does not tilt downwardly for the reason that an intermediate roller bearing pin 37^f will then be in contact with the wide end section of the track and supports the tray against such tilting movement, and before the pin 37^f will have moved off the end section 34^a the forward pin 37^e will have moved across the gap or space between the end of section 34^a and the adjacent end of a short horizontal section 34^b of the upper track, and hence the tray will still be supported positively in horizontal position. As the rear roller pin 37^d passes off the end of the section 34^a of the track to the position of tray B of Fig. 3, the forward roller pin 37^e will have been engaged by the upper end of the transfer arm 38. From the position of tray A shown in full lines in Fig. 3, the tray begins to descend, the forward end thereof in the arc described by the upper end

of transfer arm 38 and the rear end of the tray in the arc of the sprocket 26, the pin 37^d passing through the gap or cutout in the track above mentioned. The distance between the centers of the pins 37^e and 37^d of each tray is the same as the distance between the centers of the shaft 38^a, and the shaft 30. Since the length of the arm 38 corresponds to the diameter of the sprocket 26, 27 the tray is retained in horizontal position 10 in its downward movement from the position of tray B to the position of tray C wherein both front and rear pins 37^e rest on the bottom track 35 which at the forward end thereof is extended, as shown in Fig. 3, to form an arcuate guide 35^a 15 against which the roller of pin 37^e may contact during the descent or transfer of the tray from the upper to the lower track as described.

If it be assumed that the direction of movement is the reverse of that described above, the transfer of a tray in the position C to position B takes place somewhat similarly. Thus in the position of tray C the lower end of the arm 38 engages the pin 37^e of the tray and begins to elevate it arcuately in synchronism with the arcuate elevation of the rear pin 37^d which, as above described, constitutes a pivot for adjacent pairs of links of the chain and is supported by the latter. As a tray moves clockwise from the position C to position B, the arm 38 carries the pin 37^e 25 around the forward end of the track section 35^a from which it is released as the pin moves to the right and the arm continues its clockwise movement. In proceeding from position B to position A, a tray is retained in horizontal position by 30 reason of the fact that roller pin 37^e will not have moved to a position over the cutout or gap between the right-hand end of track section 34^b and section 34^a until the roller pin 37^b will have made rolling contact with the adjacent end of 35 the main section 34 of the track.

Since both sides of the transfer mechanism at the forward end operate similarly and operate in synchronism, the trays are positively supported in horizontal position during the transfer from 40 one run of the conveyer to the other.

At the opposite end of the traveling mechanism the operation is the same in principle, but in providing for movement of the conveyer in both directions slightly different mechanism must be employed, since at the right end (which is assumed to be the rear end of the oven by reason of the illustrated arrangement of the trays) the front ends of the trays are moved in arcuate paths which are located between the opposite 50 chains 24 and 25 whereas at the forward end of the oven the front end of the trays move in arcuate paths located forwardly of the carriers and horizontal portions of the tracks.

At the rear or right hand end portion of the traveling mechanism there is provided a pair of sprockets 44 and 45 which mesh with the drains 24 and 25 respectively and which are located forwardly of the sprockets 28 and 29 a distance corresponding to the longitudinal spacing of the axes of the shafts 30 and 38^a. The sprockets 44 and 45 are mounted on a transverse shaft 46 on which, at each side of the oven is mounted a transfer arm 47, corresponding to the arms 38.

The lower tracks 35 adjacent the right hand end portions thereof are provided each with a pivotally mounted section 48 secured to shafts 49 and constituting a track switch between the intermediate horizontal portion of the track 35 and an arcuate portion 35^b (similar to portion 70 75 35^a) which extends to the rear of and in proper

proximity to the sprocket 44. The switch members 48 are arranged to operate within slots formed in the tracks 35 (see Fig. 6) which extend to the right to positions beneath the sprockets 28 and 29 as illustrated in Fig. 3. Secured to each switch shaft 49 is a cam follower arm or lever 50 provided with followers 51 which contact cams 52 mounted on the shaft 48 at each side of the oven. Counterweights 53 are shown (Fig. 2) for retaining the followers 51 in contact with the cams 52.

Referring to Fig. 3, let it be assumed that the traveling mechanism is moving clockwise. Tray in position D will move to the right, and as the roller pin 37^c at the forward or left hand free end of the tray moves off the right hand end of the upper track 34, it is engaged by the upper portion of the transfer arm 47 as illustrated by the tray in position E. The tray is thus supported at its forward end by the arms 47 at each side of the oven and at its rear ends by the pins 37^d which are connected to the chains. As the tray moves downwardly from position E, it is retained in horizontal position by reason of the fact that the axes of the pins 37^c and 37^d move through similar arcs at the same rate, the sprockets 44 and 45 being driven by the respective chains 24 and 25 at the same angular velocity as that of the sprockets 28 and 29. During the descent of the tray from position E to position F, the curved track portions 35^b retain the pins 37^c against dislodgment from the recesses 47^a in ends of the arms 47 and as the pins 37^c reach the lower ends of the track sections 35^b, they contact the track switches 48, which then are in the position shown in Fig. 3, and move along the same to the horizontal section of the track concurrently with the movement of the pins 37^d from their arcuate paths to the horizontal paths along the rear or right hand portions of the lower tracks 35. During the last described portion of the movement of the tray, the switches 48 are retained in the operative positions shown in Fig. 3 by one of the dwells 52^a of each cam 52 but as the rear pins 37^d approach the track switches as the tray moves to the left from position F, the cams permit the counterweights to shift the switches 48 downwardly, as shown in Fig. 1, whereby the rear pins 37^d of the tray can move horizontally from position F toward position G of Fig. 3. Each tray as it approaches the position E as the conveyer moves clockwise is thus engaged by the transfer arms which, in cooperation with the sprockets 28 and 29, cause the trays to be shifted from the upper to the lower runs of the chains while positively maintaining their horizontality.

If it be assumed that the conveyer chains are moving counterclockwise as viewed in Fig. 3, a tray moving to the right from position G to the position F travels horizontally on the lower tracks. As it reaches the position F, the lower ends of the arms 47 will have moved into engagement with the forward pins 37^c and the cams 52 will have elevated the track switches 48 from the position shown in Fig. 1 to the position shown in Fig. 3. Such shifting of the switches will not have occurred until the rear pivot pins 37^d have moved beyond or to the right of said switches. The switches when in the position of Fig. 3 direct the pins 37^c upwardly in an arcuate path into rolling contact with the inner face of the curved track section 35^b, such movement taking place simultaneously with the similar upward arcuate movement of the pins 37^d as the latter move around the sprockets 28, 29. When the tray has

reached the position of tray E during such counter-clockwise movement, it assumes a horizontal movement to the left toward position D and as it moves from position E the forward pins 37^c obtain support on the ends 34^b of the track sections 34 (see Fig. 4) for supporting the forward ends of the trays as disengagement occurs between those pins and the transfer arms 47.

From the above description it will be seen that the trays are positively held in horizontal relation during the transfer of the same from one run of the conveyers to the other and since the means for retaining them in such relation is disposed largely in the space between the planes of the upper and lower runs, the mechanism can be accommodated in a baking chamber of relatively small vertical dimensions as compared, for example, with pendant tray ovens.

For the purpose of maintaining the chains suitably taut and accommodating the contraction and expansion thereof, we have shown the shafts 28^a, 29^a and 46 journaled in slideable bearing 54. (See Fig. 7 where the bearing at one side only of the oven is shown.) The bearing 54, which supports one end of the shaft 46 and also the shaft 29^a, is mounted in channel members 55, 56 which are slidably positioned between the channel-shaped guides 57, 58 which may be suitably attached to the oven frame and arranged flush with the inner surface of the furnace side wall. Brackets 59, 60 depend from the slide members 55, 56 for supporting the cam shaft 49. An abutment plate 61 (see Fig. 3) is located between the stationary members 57, 58 against which a spring 62 bears at one end while the other end of the spring presses against the end of the slideable bearing structure as shown in Fig. 7. The springs 62 (one at each side of the furnace) tend to move the movable bearings to the right as viewed in Fig. 7 and thus retain suitable tension on the chains 24 and 25 and accommodate the contraction and expansion of the chains under the influence of different temperatures. The curved track sections 35^b also are mounted respectively on the corresponding slideable bearing structure and hence retain their relationship with the corresponding track switch members 48 during the slight displacements of the movable bearings that may occur due to temperature changes to which the chains are subjected. Hence the slight elongation of the chains that may occur do not disturb the proper spaced relationship of the shafts 46 with respect to shafts 28^a, 29^a, nor of the members 48 with respect to members 35^b nor the synchronism of the operation thereof.

In Fig. 5 a rail 63 as shown slightly spaced above the upper rear of the chain 25 to restrain upward movement of the chain due to vibration or other causes, particularly where the improvements are embodied in a portable oven as in an army field oven, for example. Similar rails are provided for the upper run of the chain 24 as well as for the lower runs of the chains, but they have been omitted from the other figures of the drawings for the purpose of avoiding confusion and obstruction of other illustrated parts.

The mechanism shown and described supports the pans of bakery products placed on the trays 37 in horizontal positions throughout the cycle or cycles of travel of the same within the baking chamber and thereby prevent the settling or running of the dough or batter to a side of a pan and the production of deformed products. Inasmuch as the trays are stabilized or positively supported in such horizontal relation, the baker

need not attempt to balance the loads placed on the trays and hence the oven can be loaded with less care and with greater expedition than where tiltable trays are employed. The reduction in the vertical height of the baking chamber, as compared with conventional pendant tray ovens, not only conserves the use of construction materials but less stratification of heat in the relatively low baking chamber occurs and a more uniform temperature may be maintained within the oven. Likewise, the reduction in height of the oven made possible by the present improvements renders possible the installation of the oven in relatively low ceiling rooms without such substantial building alterations as frequently are necessary in installing ovens of the prior type.

While we have shown and described an improved oven of the reversible type, that is, one in which the direction of travel may be reversed since such arrangement is considered desirable in some instances of use, it will be apparent that such mode of operation is not essential to the utilization of the principle of this invention, hence we do not wish to be restricted thereto nor to the specific embodiment of the invention which has been shown for the purpose of illustration.

We claim:

1. A bake oven conveyer comprising a pair of endless parallel chains having horizontal upper and lower runs, pairs of front and rear sprockets around which the chains pass, means for operating said chains, trays each pivotally attached at one end thereof only to said chains, horizontal tracks beneath the horizontal runs of the chains for supporting the same and for supporting the unpivoted ends of said trays during movement of the latter by the horizontal runs of the chains, transfer mechanism located adjacent one pair of sprockets for engaging the unpivoted ends of said trays for retaining the same in horizontal relation as the pivoted ends thereof are carried around said pair of sprockets in moving from one horizontal run to the other, a second transfer mechanism located adjacent said other pair of sprockets for engaging said unpivoted ends of said trays and moving the same arcuately for retaining the trays in horizontal relation as the pivoted ends thereof are moved arcuately about said other pair of sprockets in passing from one horizontal run of the chains to the other, said second transfer mechanism comprising arcuate track members disposed between the upper and lower tracks and spaced from the latter, movable switches adjacent said lower tracks, and means for moving said switches into non-switching positions as the pivoted ends of said trays pass through the spaces between said arcuate track members and said lower tracks and for moving said switches into operative switching positions as said unpivoted ends of said trays approach said spaces for effecting cooperation of said switches with said second transfer mechanism in directing said unpivoted ends of the trays across said spaces.

2. A bake oven conveyer comprising a pair of endless parallel chains having horizontal upper and lower runs, pairs of front and rear sprockets around which the chains pass, means for operating said chains, trays each pivotally attached at one end thereof only to said chains, horizontal tracks beneath the horizontal runs of the chains for supporting the same and for supporting the unpivoted ends of said trays during movement of the latter by the horizontal runs of the chains, transfer mechanism lo-

cated forwardly of one pair of sprockets for engaging the unpivoted ends of said trays for retaining the same in horizontal relation as the pivoted ends thereof are carried around said pair of sprockets in moving from one horizontal run to the other, and mechanism adjacent said other pair of sprockets for maintaining the trays in horizontal relation during the movement of the trays about said other pair of sprockets from one horizontal track to the other comprising arcuate track sections disposed between said upper and lower tracks and spaced at the lower ends from the respective lower tracks, track switches movable into said spaces between said lower tracks and said arcuate tracks, rotatable members each arranged to engage the unpivoted end portions of said trays and to move the same along said switches and arcuate tracks for retaining the trays in horizontal relation as the pivoted ends thereof are moved about said other pair of sprockets, and cam means for operating said track switches out of said spaces to enable the pivoted ends of the trays to move beneath said arcuate track members along said lower horizontal tracks.

3. A bake oven conveyer comprising a pair of endless parallel chains having horizontal upper and lower runs, pairs of front and rear sprockets around which the chains pass, means for operating said chains, trays each pivotally attached at one end thereof only to said chains, horizontal tracks beneath the horizontal runs of the chains for supporting the same and for supporting the unpivoted ends of said trays during movement of the latter by the horizontal runs of the chains, transfer mechanism located adjacent one pair of said sprockets for engaging the unpivoted ends of said trays for retaining the same in horizontal relation as the pivoted ends thereof are carried around said pair of sprockets in moving from one horizontal run to the other, and mechanism adjacent said other pair of sprockets for guiding the unpivoted ends of the trays arcuately for retaining the trays in horizontal relation as the pivoted ends thereof are moved arcuately in succession about said other sprockets from one horizontal track to the other, said mechanism comprising arcuate track sections disposed between the upper and lower horizontal tracks and being spaced from the latter to enable the pivoted ends of the trays to pass beneath said arcuate tracks, track switches arranged for movement into said spaces to form extensions of said arcuate tracks and projecting into the plane of the lower tracks for guiding the unpivoted ends of the trays across said spaces, means for operating said switches to and from said guiding positions in timed relation with respect to the movements of the trays beneath said curved tracks, and a pair of rotatable members cooperable with said arcuate tracks and said switches for engaging unpivoted portions of said trays and moving the same along said switches and arcuate tracks in synchronism with the arcuate movement of the pivoted ends of the trays about said other sprockets.

4. An oven conveyer comprising a pair of parallel endless chains having horizontal runs, sprockets around which said chains pass, horizontal tracks beneath said horizontal runs of the chains for supporting the same, said tracks extending inwardly of the said chains, trays disposed between said chains and pivotally secured at one end only of each to opposite portions of the chains, said trays having laterally project-

ing anti-friction members at the unpivoted ends thereof arranged for rolling contact with said inwardly projecting portions of said tracks for supporting the trays in horizontal relation during movement thereof through the ranges of the horizontal runs of the chains, mechanism located adjacent one end of the chains for retaining the trays in horizontal relation as the pivoted ends thereof pass in succession about the adjacent sprockets, and means adjacent the other sprockets for supporting the unpivoted ends of the trays as the pivoted ends thereof move about said other sprockets, said means comprising a pair of rotary transfer members and cooperating arcuate track members arranged in the vertical planes of the inwardly extending portions of each upper and the respective lower tracks, said arcuate track members being spaced above the respective lower tracks to permit said pivoted ends of the trays to pass therebeneath, said lower tracks having slots therein adjacent the lower ends of said arcuate tracks, and cam controlled switches operable within said slots and arranged for movement into positions to bridge said spaces for cooperation with said rotary members in moving the unpivoted ends of the trays across the spaces between the arcuate tracks and said lower tracks.

5. A conveyer for bake ovens comprising a pair of endless parallel reversibly operable chains having horizontal upper and lower runs, a plurality of trays each having one end thereof only pivotally attached to opposite ends of the chains, horizontal tracks beneath the horizontal runs of said chains adapted to support the unpivoted ends of said trays in horizontal relation during movement thereof by the horizontal runs of the chains, rotary transfer means adjacent one end of the conveyer for retaining said trays in horizontal relation during movement thereof from one run of the conveyer to the other, arcuate track members disposed between the upper and lower tracks adjacent the other ends thereof and spaced therefrom, movable switches in the spaces between said arcuate track members and the lower of the said horizontal tracks at said last mentioned end of the latter and adapted to direct the unpivoted end of each tray across the spaces between said arcuate track members and the lower of said tracks, rotary means for engaging said unpivoted ends of the trays in succession for moving the same along said arcuate tracks and switches for retaining said unpivoted ends of the trays in horizontal alignment with the respective pivoted ends thereof as the trays move from one run of the chains

to the other at said end of the conveyer, and means for moving said switches into non-switching positions as the pivoted ends of the trays pass through said spaces and for moving said switches into operative switch positions as said unpivoted ends of said trays approach said spaces.

6. A bake oven conveyer comprising a pair of spaced apart parallel endless chains having upper and lower horizontal runs, sprockets at the ends of the conveyer around which said chains pass, trays between the chains each pivoted at one end to opposed portions of the chains and being free at the other end, horizontal tracks disposed adjacent each of the horizontal runs of the chains for retaining said trays in horizontal relation during movement thereof by the horizontal runs of the chains, means at one end of the conveyer for engaging the free ends of the trays in succession for retaining the trays in horizontal relation as the pivoted ends thereof move about the adjacent sprockets in passing from one horizontal run of the conveyer to the other, stabilizing means at the opposite end of the conveyer for engaging said unpivoted ends of the trays in succession for retaining the trays in horizontal relation as the pivoted ends thereof move about the adjacent sprockets, said stabilizing means comprising rotary tray engaging members, arcuate track members cooperable with said rotary members and spaced at the lower ends from said lower horizontal tracks to enable the pivoted ends of the trays to pass beneath the same in moving to and from the adjacent sprockets, track switches movable into operable positions within said spaces as the unpivoted ends of the trays approach said spaces to provide arcuate track extensions cooperable with said transfer means for moving said unpivoted ends of the trays across said spaces, cam means for indexing said track switches into said operable positions and out of said positions in timed relation with respect to the movements of successive trays to enable the pivoted ends of the trays to pass through said spaces, and means for maintaining said chains taut during expansion and contraction thereof comprising longitudinally slidable means in which said rotary members, said cam means, said arcuate tracks and adjacent sprockets are supported for effecting movement of said supported means as a unit for preserving the indexed operating relation of the same during expansion and contraction of said chains.
